(57) **CLAIM**

The ornamental design for an assembly of syringe plunger rod with clicking mechanism, as shown and described.

DESCRIPTION

FIG. 1 is an assembled perspective view of the syringe plunger rod and clicking mechanism;

FIG. 2 is an exploded perspective view of the syringe plunger rod in alignment with the clicking mechanism, with the dashed lines depicting how the clicking mechanism is assembled to the syringe plunger rod;

FIG. 3 is a component perspective view illustrating the syringe plunger rod and the clicking mechanism in a side-by-side relationship;

FIG. 4 is a component front elevational view illustrating the syringe plunger rod and the clicking mechanism in a side-by-side relationship;

FIG. 5 is a component rear elevational view illustrating the syringe plunger rod and the clicking mechanism in a side-by-side relationship;

FIG. 6 is a component left side elevational view illustrating the syringe plunger rod and the clicking mechanism in a side-by-side relationship;

FIG. 7 is a component right side elevational view illustrating the syringe plunger rod and the clicking mechanism in a side-by-side relationship;

FIG. 8 is a component top plan view illustrating the syringe plunger rod and the clicking mechanism in a side-by-side relationship; and,

FIG. 9 is a component bottom plan view illustrating the syringe plunger rod and the clicking mechanism in a side-by-side relationship.
